INTERNAL COMBUSTION ENGINE

George M. Bicknell, St. Louis, Mo., assignor to
Waukesha Motor Company, Waukesha, Wis., a
corporation of Wisconsin

Application June 17, 1929, Serial No. 371,534

2 Claims. (Cl. 123—191)

This invention relates to improvements in internal combustion engines and particularly to the provision of a combustion chamber of an improved design and also to valve cooling arrangements for such engines.

Heretofore, difficulty has been experienced in engines of this nature due to preignition and detonation of the fuel charge. I have found that this difficulty can be remedied to a great extent 10 by concentrating the main volume of the fuel charge at the time of combustion in a part of the combustion chamber which is comparatively cool.

Exhaust valves of the usual poppet type have practically their whole surface exposed directly 15 to the flame during the exhaust cycle, and since the only paths of escape for the heat are through the seat and stem of the valve, the heads of these valves sometimes become unduly hot or even incandescent, resulting in deterioration of the 20 metal and preignition and detonation of the charge.

It is an object of this invention to produce a combustion chamber for internal combustion engines in which the main part of the volume will 25 be concentrated in a part of the chamber which is comparatively cool—in other words, to concentrate the volume of the combustion chamber adjacent the coolest parts of its walls. It will be understood, of course, that the walls of the 30 chamber include the heads of the inlet and exhaust valves as well as the top of the piston.

It is a further object of this invention to produce an engine having valves of the poppet type and of such construction and arrangement that 35 a minimum portion of the surface of the valve will be exposed to the flame of the exhaust. Other objects of the invention will appear from the following specification and the accompanying drawings, referring to which:

Figure 1 is a sectional plan view of an engine 40 constructed in accordance with my invention taken along the line 1—1 of Figure 2.

Figure 2 is a sectional elevation, taken along the line 2—2 of Figure 1.

Figure 3 is a sectional elevation taken along the line 3—3 of Figure 1.

Figure 4 is a sectional elevation taken along the line 4—4 of Figure 1.

Figure 5 is a sectional elevation taken along the line 5—5 of Figure 1.

For convenience of illustration, an engine having a single cylinder has been shown. It will be obvious that the invention is applicable to engines having any number of cylinders.

The reference numeral 1 indicates an internal

combustion engine cylinder having a head 2 and a combustion chamber generally indicated at 3. The cylinder is provided with the usual water jacket 4 and the head is also jacketed to contain a cooling fluid as indicated at 15.

Inlet and exhaust valves 5 and 6, respectively, of the conventional poppet type are provided. A conventional piston 7 operates in the cylinder 1. The formation of the piston chamber in the cylinder head is such that a greater part of the 10 volume of the combustion chamber is adjacent the inlet valve than in prior constructions. An upwardly extending portion of the combustion chamber, as indicated, at 8 is located adjacent the inlet valve.

This portion of the chamber is arranged to contain the greater part of the volume, and the wall of the chamber is so formed as to leave only a comparatively thin layer of gas between the greater part of the piston head and the wall of 20 the chamber.

That portion of the wall of the combustion chamber which is over the exhaust valve is so formed that when the exhaust valve is open, there will be only a very small clearance between the top 25 of the valve and the top of the combustion chamber. Some clearance is, of course, necessary for tolerance in manufacturing and operation, but the space is so reduced, as indicated at 9, that there will be substantially no flow of flaming 30 gas over the top of the exhaust valve during the exhaust cycle. The proximity of the top of the exhaust valve to the water cooled surface of the combustion chamber results in a more efficient 35 cooling of the valve, and at the same time the valve protects a part of the wall of the combustion chamber from the flame, resulting in a cooler operating motor generally.

The reduction of volume of the combustion chamber at the point above the exhaust valve and above the greater part of the piston head results in the reduction of volume at all points except adjacent the inlet valve which is comparatively cool in operation due to the passage 40 through it of the cool fuel gas. This construction results in a number of advantages, some of which are as follows:

The reduction in the thickness of the layer of fuel directly above the piston results in the transmission of less heat to the piston during that part 50 of the cycle in which the piston is at the top of its stroke, and the proximity of the top of the piston to the cooled wall of the cylinder head results in the comparatively free transmission of heat away from the piston top. The piston be- 55

ing rather difficult to cool effectively is, in any case, likely to get very hot and cause detonation, and this reduction in the amount of heat transmitted to it results in lower operating temperatures and less likelihood of detonation as well as in leaving a smaller amount of gas subject to the detonation in case it should occur under extreme operating conditions. The reduction in volume of the combustion chamber adjacent the exhaust valve also has the same advantages.

In modern automobile engine construction, it is customary to make a plurality of the cylinders in a single block and to have the water jacket of the head of a substantially flat and rectangular construction, that is to say, the outer wall of the water jacket usually lies in a plane substantially perpendicular to the axis of the cylinder. By enlarging the space above the inlet valve, I have reduced the thickness of the water jacket, as indicated at 10. This portion of the combustion chamber being normally cooled to a considerable extent by the cool fuel from the inlet manifold does not in any case become as hot as other portions of the combustion chamber. At the same time, the spark plug 11 does not have to pass so far through the water jacket, and a comparatively short plug may be used.

The reduction in volume of the combustion chamber at the point above the exhaust valve results in a maximum thickness of the water jacket at that point, as indicated at 11a, thereby giving a large volume of water or other cooling fluid at this point, which requires more cooling than any other portion of the combustion chamber.

In operation, the valves 5 and 6 and the piston 7 are reciprocated by conventional means (not shown) in such a manner as to produce the well-known four-cycle operation. Near the end of the power stroke, the exhaust valve 6 is opened to such a position that its head is in proximity to the wall 2 of the combustion chamber, as indicated at 9. Such portions of the exhaust gas as

come into contact with the exhaust valve at all during this portion of the cycle come in contact only with the stem and the under surface of the head of the valve. There is, of course, some gas in contact with the upper surface of the valve, but it is a thin layer, flowing at a comparatively slow rate, so that the heat transmitting effect is less. The heat taken up by the lower surface and stem of the exhaust valve is conducted down the stem of the valve from which it may be dissipated by the action of the water jacket 4.

I claim:

1. In an internal combustion engine of the L-head type, a combustion chamber having inlet and exhaust valves opening into the said chamber, said chamber having a portion of great depth adjacent the inlet valve and a portion of less depth adjacent the exhaust valve, said portions of the combustion chamber being in direct communication, said chamber having a third portion of less depth than that portion adjacent the exhaust valve, said third portion being directly adjacent the piston of the engine when it is at the top of its stroke, the cylinder roof overlying said third portion being inclined upward toward and merging into the roof of said first portion and the roof of said second portion, the roof of said second portion being inclined upward toward said first portion and merging into the adjacent wall of the latter.

2. In an internal combustion engine of the L-head type, a cylinder and a piston operating therein, a combustion chamber lying to one side of and opening into said cylinder, inlet and exhaust valves arranged side by side in said chamber, the latter defining a relatively shallow pocket over the exhaust valve and a relatively high pocket over the inlet valve, said pockets opening freely one into the other, and a spark plug mounted in the roof of said relatively high pocket in alignment with and overlying said inlet valve.

GEORGE M. BICKNELL.
